Primary Examiner — Thomas Johannes*Assistant Examiner* — Chelsea Sealey(74) *Attorney, Agent, or Firm* — J.C. Patents(57) **CLAIM**

The ornamental design for a cover, as shown and described.

DESCRIPTION

FIG. 1 is a perspective view of a cover showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along line 8-8 in FIG. 2; and,

FIG. 9 is another cross-sectional view thereof taken along line 9-9 in FIG. 2.

The broken line portions of the cover in all views represent unclaimed portions of the claimed design and form no part thereof.

1 Claim, 7 Drawing Sheets(56)
